S. T. NELSON

FORGING MACHINE

Original Filed Jan. 26, 1923

Inventor
Sp³³en T. Nelson.

attorney.

UNITED STATES PATENT OFFICE.

SVEN T. NELSON, OF MICHIGAN CITY, INDIANA, ASSIGNOR TO SULLIVAN MACHINERY COMPANY, A CORPORATION OF MASSACHUSETTS.

FORGING MACHINE.

Application filed January 26, 1923, Serial No. 615,021. Renewed July 21, 1927.

My invention relates to forging machines, and more particularly to forging machines for use in sharpening cutter bits and similar implements.

5 An object of my invention is to provide an improved forging machine. A second object of my invention is to provide an improved forging machine having improved die means for the formation and sharpening 10 of blanks or dulled cutting implements. Other objects and advantages of my invention will hereinafter more fully appear.

In the accompanying drawings I have shown for purposes of illustration one form 15 which my invention may assume in practice.

In these drawings,

Fig. 1 is a central longitudinal vertical section through a forging machine constructed in accordance with the illustrative embodiment of my invention.

Fig. 2 is an enlarged view similar to Fig. 1 with portions broken away to show details of construction, this view being more nearly a complete central section.

25 Fig. 3 is a front elevation of the forging mechanism proper.

In the form in which I have illustrated my invention, the same comprises a main frame made up of a bed casting 1 supported 30 on a series of legs 2. The bed casting is provided with parallel guides 3 and 4 and in substantially the same horizontal plane with the guides is arranged a transversely extending crank shaft 5 driven by a combined driving pulley and flywheel 6 and having a crank pin 7 connected by a connecting rod 8 with a crosshead 9 slidable in the guides 3 and 4. The crosshead carries therewith and pivoted upon a transversely extending pivot 10 disposed adjacent the forward end thereof, a relatively heavy frame member 11 whose angle of oscillation about the pivot 10 is limited as to oscillation forwardly by a stud 12 extending through a hole 13 disposed to the rear of the pivot, the stud being screwed into the crosshead 9. A heavy spring 15 whose tension is adjustable by adjusting a plunger 16 extends between the rear end of the pivoted member 11 and the crosshead 9 and maintains the member 11 always in the farthest position to which it can turn in a clockwise or forward direction.

Pivoted to the casting 11 in front of the

pivot as at 17 is a clapper box 18 which carries rotatably mounted on a pair of parallel heavy studs 19 a pair of annular dies 20 which cooperate to form a forming groove 21. These dies 20 practically contact at their upper portions 22, while they are cut away at their lower portions 22' to form 60 grooves whose combined cross section is the same as the desired cross section of the tool to be sharpened thereby. Upon the bed plate 2 between and below the guides 3 and 4 is mounted a supplemental frame member 23 65 which carries a stationary die member 24 whose position may be adjusted by an adjusting screw 25, this die being arranged in alinement with the path of reciprocation of the dies 20 and being adapted completely to fill the groove provided between the lower portions of the dies 20 as the dies roll across it. Slidable transversely of the supplemental frame 23 is a member 26, which member is located just to the rear of the stationary die 24. The member 26 is provided with a bit or blank receiving slot 27 whose back and side walls are formed in the member 26, but which has an open front closed, in the working position of the member 26, by a surface of the frame member 23 and the stationary die 24. Suitable means for sliding the frame 26 laterally to effect discharge of a finished blank or bit is provided, but, as this mechanism forms no material part of my present invention, it requires no explanation, other than to say that by manipulation of a lever 28 the movable member 26 may be slid back and forth to discharge a bit.

90 For the purpose of adjusting the vertical position of the bits in order that sufficient metal may be projected into the path of the moving dies 20 to fill out completely the points of the bits which are to be formed, 95 I provide a sliding wedge 30 having an inclined surface 31 upon which the lower end of a blank 32 is adapted to rest, the wedge member 30 having a rack 33 formed at the bottom thereof and being longitudinally 100 movable by a toothed sector 34 secured on a rock shaft 35 for which suitable adjusting and locking means (not shown) is provided. It will be noted from Figure 2 that the wedge member constitutes an interlocking means for 105 preventing possible lateral slipping of the

bit holder during the course of sharpening. The mode of operation of my improved mechanism will be readily apparent. Assume that the slide 26 is in its proper position with the slot 27 therein in alinement with the groove between the dies 20 and that the wedge member 30 has been moved to lock the member 26 against movement. A heated blank is then slipped into the slot 27 and slides to rest upon the inclined surface 31 of the wedge member 30. The pulley 6 is then caused to rotate the crank shaft 5 in any suitable manner and the lower surfaces of the dies 20 engage the end portion of the drill bit or blank if the sliding wedge 30 has been suitably adjusted by the operator to bring this about. The dies 20 will then roll the projecting material out into such form as to completely fill up the groove between the dies 20 as this groove moves along and will also draw out the point of the blank to a shape as indicated in Fig. 2. The upper portions 22 of the dies 20 are so close together that no substantial escape of material between the dies is possible and, by virtue of the fact that a plurality of dies are used, any jamming action of the metal is entirely impossible.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. A forging machine for forming the cutting ends of cutter bits comprising a raised die against which the front face of the bit is to be formed, die means including a plurality of cooperating grooved dies for forming substantially simultaneously the other surfaces of the cutting ends, said raised die being adapted to project within the grooves in said other dies, and means for causing relative movement between said projecting die and said grooved dies to effect forming of said cutting end.

2. A forging machine for forming the cutting ends of cutter bits comprising a projecting die against which the front face of the bit is to be formed, die means including a plurality of grooved rotatable dies for forming substantially simultaneously the other surfaces of the cutting end, said projecting die being adapted to extend within the grooves in said rotatable dies, and means for effecting relative movement between said projecting die and said rotatable dies to effect forming of said cutting end.

3. In a forging machine, a stationary projecting die, a pair of cooperating forming dies rotatable on parallel axes at opposite

sides of said other die, said projecting die being adapted to extend between said other dies, and means for effecting movement of said rotatable dies relative to said projecting die.

4. In a forging machine, a raised die, a pair of cooperating grooved dies rotatable on parallel axes, said raised die being adapted to project upwardly within the grooves in said other dies, and means for effecting movement of said rotatable dies relative to said raised die.

5. In a cutter bit forging machine, a stationary raised die, a pair of cooperating grooved roller dies disposed on parallel axes and adapted to move in a straight path, means for supporting a bit blank at an acute angle relative to said path, and means for effecting movement of said roller dies relative to said stationary die for forming the cutting end of the bit with clearance.

6. In a cutter bit forging machine, a projecting die having lateral surfaces and a supporting surface, a pair of dies each having a lateral surface cooperating with a lateral surface on said other die, said projecting die and said pair of dies being relatively movable, means for supporting a blank adjacent said projecting die and at an angle to the direction of said relative movement, and means for effecting relative movement between said projecting die and said grooved dies to effect forming of the cutting end of the bit with clearance.

7. In a forging machine, a projecting die, a pair of cooperating dies arranged to act simultaneously on a work piece, said projecting die being adapted to extend between said other dies, and means for effecting relative movement between said projecting die and said pair of dies.

8. In a cutter bit forging machine, a projecting die, a pair of cooperating dies, said projecting die being adapted to extend between said other dies, a pivotal mounting for said cooperating dies, and means for effecting relative movement between said projecting die and said other dies to effect forming of the cutting end of the bit.

9. A cutter bit forging machine comprising a projecting die against which the front face of the bit is to be formed, a plurality of cooperating dies cooperating with said projecting die to form the other surfaces of said cutting portion, said projecting die being adapted to extend between said other dies, a pivotal mounting for said plurality of cooperating dies, and means for effecting relative movement between said projecting die and said other dies.

10. In a forging machine, a pair of cooperating forming dies having surfaces cooperating to form a groove, a complementary raised die adapted to extend into the groove formed by said pair of dies, and

means for effecting relative movement between said cooperating dies and said raised die.

11. In a forging machine, die means comprising a plurality of cooperating dies having lateral surfaces forming a groove, a complementary raised die having lateral surfaces adapted to cooperate with the lateral surfaces of the groove formed by said other dies, and means for effecting movement of said cooperating dies relative to said raised die.

12. A forging machine for forming the cutting ends of cutter bits comprising a projecting die against which the front face of the bit is to be formed, die means including a plurality of dies for forming substantially simultaneously the other surfaces of the cutting end, said projecting die being adapted to extend between said other dies, and means for causing relative movement between said die and die means to effect forming of said cutting ends.

13. A forging machine for forming the cutting portions of cutter bits comprising a projecting die against which the front face of each bit operated upon is to be formed, cooperating die means having lateral surfaces cooperating with the lateral surfaces of said projecting die for forming the other surfaces of the cutting portions, and means for effecting relative movement between said die and die means, said die means including a die rotatable on an axis lying in a plane to which both the longitudinal axis of the bit in process of formation and the direction of said relative movement between said die and die means are parallel.

14. A forging machine for forging the cutting ends including the face of cutter bits comprising a projecting die against which the front face of the bit is to be formed, die means including a plurality of separate dies each adapted to form only one of the other surfaces of the cutting end, said projecting die being adapted to extend between said separate dies, and means for causing relative movement between said die and die means to effect forming of said cutting ends.

15. A cutter bit forging machine comprising a die against which the front face of a bit is to be formed, and a plurality of swingingly mounted dies cooperating therewith to form the other surfaces of said cutting portion, and means for causing relative movement between said dies.

16. A bit forging machine for forming the cutting portion of a cutter bit including the cutting face thereof comprising a holder for receiving the shank end of a bit blank, a plurality of dies each adapted to form only one side of the cutting portion of the bit, and a raised die against which the front face of the bit is to be formed, said raised

die being adapted to project between said other dies.

17. A bit forging machine for forming the cutting portion of a cutter bit comprising a blank holder, a die adapted to form only one lateral bounding surface of the cutting portion of the bit and movable over said surface during forming thereof, and a projecting die having a lateral surface adapted to cooperate with the lateral surface on said other die.

18. A bit forging machine for forming the cutting portion of a cutter bit including the cutting face thereof comprising a blank holder, a plurality of separate dies for forming the lateral bounding surfaces of a cutting portion of a bit, the axes of said latter dies being disposed laterally of said surfaces, and a projecting die adapted to extend between said separate dies.

19. A forging machine for forming cutting ends on cutter bit tools comprising a projecting die against which the front face of the tool is to be formed, die means including a plurality of symmetrically arranged dies each adapted to form but one of the other bounding surfaces of the cutting end, said projecting die being adapted to extend between said other dies, and means for causing relative movement between said die and die means to effect forming of said cutting ends.

20. A forging machine for forming cutting ends on tools comprising a die against which the front face of the tool is to be formed and die means including a pair of rotatable dies cooperating to form between them a groove whose cross section corresponds to the cross section of the first mentioned die formed on cutting said die by a plane parallel to a plane including the axes of rotation of said second mentioned dies, and means for causing relative movement between said die and die means to effect forming of said cutting ends.

21. In a forging machine, a stationary raised die, a ram movable relative to said stationary die, and a pair of cooperating dies supported on said ram and rotatable on axes spaced at opposite sides of said first mentioned die, the latter die being adapted to extend between said other dies.

22. In a forging machine, three cooperating dies, cooperating among themselves to form all of the bounding surfaces of the cutting portion of a cutting implement and each forming a different surface from each of the others, one of said dies being adapted to extend between said other dies, and means for effecting relative movement between said die and said other dies.

23. A cutter bit forging machine comprising a raised die against which the front face of a cutter bit is formed, the transverse section of said die being substantially

4

identical to the transverse section of the cutting portion of a bit formed thereon, and a plurality of rotatable dies cooperating with said other die to form the lateral surfaces of the cutting portion, said rotatable dies having their axes disposed laterally of said surfaces so that said cutting portion is formed between the peripheries of said dies.

24. A cutter bit forging machine comprising a blank holder and means for forming the lateral surfaces and cutting face of the cutting portion of a bit held thereby, said means including a raised die and a plurality of rotatable dies, the latter being adapted to form said surfaces between their peripheries and said raised die to project between said rotatable dies.

25. A cutter bit forging machine comprising a cutter bit blank holder and means for forming the cutting face and the lateral surfaces of the cutting portion of a blank held thereby, said means including a raised die and a plurality of rotatable dies, and means for effecting relative movement between said rotatable dies and said raised die, said raised die being adapted to project between said rotatable dies at a predetermined time in said relative movement whereby said surfaces may be formed between the peripheries of said rotatable dies.

26. A forging machine comprising a raised die to form the cutting face of a

cutter bit, and a plurality of rotatable dies adapted to form the lateral surfaces of a cutting portion of said bit between the peripheries of said rotatable dies.

27. A forging machine comprising means for holding the shank end of a cutter bit, dies for forging the lateral surfaces and cutting face of the bit portion of said blanks, one of said dies being adapted to extend upwardly between said other dies, and means for effecting relative movement between said dies in a direction transverse to the longitudinal axis of a blank mounted in said holding means thereby to squeeze laterally simultaneously between said other dies both sides of the bit portion during forging thereof.

28. A forging machine for forming the cutting portion of a cutter bit comprising a projecting die against which the front face of the bit is to be formed, and cooperating die means movable relative thereto and having lateral surfaces cooperating with the lateral surfaces of said projecting die for forming the other surfaces of the cutting portion, said die means including a die rotatable on an axis which traces during movement a plane generally parallel to the longitudinal axis of the bit.

In testimony whereof I affix my signature.

SVEN T. NELSON.

CERTIFICATE OF CORRECTION.

Patent No. 1,650,584.

Granted November 22, 1927, to

SVEN T. NELSON.

It is hereby certified that error appears in the printed specification of the above numbered patent requiring correction as follows: Page 1, line 53, after the word "pivoted" insert the words and numeral "as at 17", and line 54, after the word "pivot" strike out the words and numeral "as at 17" and insert instead the numeral "10"; and that the said Letters Patent should be read with these corrections therein that the same may conform to the record of the case in the Patent Office.

Signed and sealed this 17th day of January, A. D. 1928.

Seal.

M. J. Moore,
Acting Commissioner of Patents.
